UNITED STATES PATENT OFFICE.

HANS P. LUHN, OF NEW YORK, N. Y.

RAINCOAT.

Application filed April 12, 1927. Serial No. 183,032.

This invention relates to raincoats, and relates more particularly to raincoats made of paper or other cheap material and so simply constructed that they may be manufactured 5 very inexpensively and sold at such a low figure that they may be used for a single occasion and then discarded.

The primary object of the present invention is to provide an efficient raincoat of simple and cheap construction which may be sold 10 for a small sum by means of vending machines or otherwise.

A further object of the present invention is to provide a raincoat of this character which 15 provides complete protection for both the head and body of the wearer, and which may be made out of a single piece of material and requires but one seam or joint.

Other objects and advantages of this invention will be apparent from the accompanying drawings, which form a part of this specification, and in which:

Figure 1 is a plan view of a blank from 20 which a raincoat according to my invention 25 may be made;

Figure 2 is a plan view of a flap designed for use with my raincoat; and

Figure 3 is a plan view of the completed 30 raincoat.

Referring more particularly to the drawings, in which like reference numerals define like parts throughout the several views thereof, 35 10 indicates generally a blank of suitable thin inexpensive material, such as water-proofed paper. This blank is rectangular in general outline with one corner missing, the missing corner being in the shape of a right isosceles triangle. The sides of the original rectangle are marked 11, 12, 13 and 14, respectively, and 15 denotes the hypotenuse of the 40 cut off triangle.

The blank 10 is divided into several portions by the creases or folds 16, 17 and 18, which are shown in Figure 1 as dot and dash 45 lines. The fold 16 makes an angle of approximately 45° with the edges 11 and 14, and hence may be considered as the diagonal of an imaginary square, one side of which is the edge 11 continued to its point of intersection 50 with the edge 14. This fold 16 forms the back edge of the completed garment. The fold 17, which forms the top edge of the hood of the raincoat, is perpendicular to the fold 16 and crosses the same near its upper end. 55 The fold 18 is parallel to the edge 13, and forms the front edge of the garment.

The portion 19 of the blank included within the folds 16, 17 and 18 forms the entire left hand side of the raincoat. The rear and larger part of the right hand side of the coat 60 is formed by the portion 20 lying between the fold 16 and the edge 12. The portion 21 above the fold 17 comprises the front part of the right hand side of the hood of the raincoat, and the strip 22 between fold 18 and 65 edge 13 forms the extreme front part of the right hand side of the body of the raincoat. The little triangular portion 23 adjacent to the intersection of folds 16 and 17 lies between the portions 20 and 21 when the parts 70 are folded together in final position, and serves to reinforce the extreme upper corner of the garment.

A notch 24 is cut in the blank 10 along the upper end of the edge 13, and serves as an 75 aperture for the wearer's face. The lower side 25 of the notch 24 is perpendicular to the edge 13 and is preferably located near the point where fold 17 would intersect edge 13 if prolonged. The upper side 26 of the notch 80 may be perpendicular to fold 17, and is so located that the notch is large enough to permit relatively unobstructed vision through the resulting aperture in the finished raincoat. 85 At the apex of the notch 24 a second notch 27 is located, and a slit 28 is made in the blank 10 adjacent the notch 27 and conveniently as an extension of side 25 of notch 24. The purpose of the notch 27 and the slit 28 is to separate the hood partially from the body portion 90 of the raincoat, so that the hood may conform somewhat to the shape of the wearer's head or hat.

Figure 2 shows a small roughly rectangular piece 29 with chamfered edges 30 which 95 is intended to be used as a flap to cover an opening along the seam of the garment so that one of the wearer's hands may be extended therethrough.

In assembling the garment, the blank is first 100 folded along the line 18 and then along the line 17, the portions 21 and 22 being folded onto the main portion 19 as shown in Figure 3. The blank is then folded along the line 16, bringing the portion 20 over on the portion 19. 105 It will be observed that the parts are so proportioned that this folding will cause the edge 11 to lie along the edge 14, and the edge of portion 20 to overlap the edges of portions 21 and 22. The flap 29 is then placed in 110 some suitable position along the edge 13 between this edge and the edge 12, and a strip

of adhesive tape 31 or similar material is glued along the entire seam thus formed from the upper corner to the hem of the garment, as shown in Figure 3.

5 In use, the raincoat is simply slipped over the head of the wearer, and will give adequate protection for a reasonable length of time in any ordinary storm. It will be apparent that my construction is extremely simple, and calls for no buttons, hooks or fasteners of any kind. Furthermore, it will be noted that my construction embodies only a single seam, and this is an important feature of my invention, for the reason that this minimizes the cost of manufacture. In the specific embodiment of my invention disclosed herein, this seam is a straight line, which offers further manufacturing advantages, though of course it would be perfectly possible to so shape the parts that 10 the seam would be a curved or broken line, or so that more than one seam would be necessary. Moreover, the seam is located on a side of the garment, so that the outer edges of the raincoat when folded flat as shown in Figure 15 3, are seamless folds.

Another advantage of my invention resides 20 in the particular manner of constructing the seam. In my preferred construction, as illustrated, the edges to be joined together are permitted to slightly overlap, and are then cemented to each other by a strip of rubber or cloth fabric having adhesive on one side, such as the ordinary adhesive tape. A butt joint could of course be used if desired, but overlapping the edges has the advantage that there is no possibility of a portion of the adhesive being left uncovered and hence sticking to the inner side of the other half of the garment. The strip of adhesive material also 25 serves to reinforce the seam, and the resulting seam is hence much stronger than would be the case if the overlapping edges were simply glued directly together. Moreover, a taped seam as above described is more water-proof 30 than an ordinary glued joint.

A further advantage of my construction resides in the fact that there are no unwieldy pleats or folds, and that the entirely completed garment, when spread out flat, lies substantially wholly in two planes, except for the tiny reinforcing corner 23 which could, of course, be dispensed with without departing 40 from my invention. By thus having the raincoat conveniently flat and of uniform thickness, it is possible to readily fold it into a 45 convenient bundle suitable for vending.

Although the corner adjacent the edge 15

has been referred to as "cut off", it will be obvious that if several raincoats are to be cut from a single large sheet of paper, the edges 60 15 of two adjacent coats could lie along the same line, thus effecting a saving of material.

Many other changes or modifications might be made in the structure disclosed above without departing from the spirit of my invention. For example, the flap 29 might be made integral with the portion 20, in that case being located along the edge 12. The sole purpose of making it separate is to enable the raincoat to be made with a minimum waste of material, 70 as the flap 29 may obviously be cut out of the waste portions of the blank. Another slight change which might be made would be to reinforce the slit 28 and the opposed slit between the edge 25 and the upper end of edge 13 by the use of a strip of adhesive material placed over the ends of these slits, and if desired, extending part or all of the way along the same.

Although I have described a specific embodiment of my invention, I do not desire to be limited except by the prior art and the scope of the appended claims.

I claim:

1. A raincoat comprising a hood portion and a body portion both formed from a single unitary piece of material, said piece of material being divided into four portions by creases, one of said portions constituting an entire side of said coat, and the other three portions together constituting the other side, and said three portions being joined together by a single seam.

2. A raincoat comprising a hood portion and a body portion both formed from a single unitary piece of material, said piece of material being so folded in the finished garment as to be substantially wholly in two planes, said piece of material being divided into four portions by creases, one of said portions constituting an entire side of said coat, and the other three portions together constituting the other side, said three portions being so shaped that the edge of one overlaps the edges of the other two, and said overlapping edges being joined together to form a single seam.

3. The combination as claimed in claim 2 in which said seam is interrupted to form a hand opening.

In testimony whereof, I have signed my name to this specification this 6th day of April, 1927.

HANS P. LUHN.
